(57) **CLAIM**

The ornamental design for a solar fountain pump, as shown and described.

DESCRIPTION

FIG. 1 is a perspective view of a solar fountain pump showing my new design;
 FIG. 2 is another perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof;
 FIG. 9 is an enlarged detail view of area 9 circumscribed within FIG. 1;
 FIG. 10 is an enlarged detail view of area 10 circumscribed within FIG. 5; and,
 FIG. 11 is an enlarged detail view of area 11 circumscribed within FIG. 7.

The evenly spaced broken lines depict portions of the solar fountain pump that form no part of the claimed design. The dot dash dot broken lines denote the boundaries of the detail areas and detail views and form no part of the claimed design.
